W. A. HOLQUIST

WRIST MIRROR

Filed Dec. 21, 1922

INVENTOR.

WILLIAM A. HOLQUIST,

By: *Alfred Rineger*,
his Atty.

UNITED STATES PATENT OFFICE.

WILLIAM A. HOLQUIST, OF LOS ANGELES, CALIFORNIA.

WRIST MIRROR.

Application filed December 31, 1922. Serial No. 608,222.

To all whom it may concern:

Be it known that I, WILLIAM A. HOLQUIST, a citizen of the United States, residing at Los Angeles, in the county of Los Angeles and State of California, have invented a new and useful Wrist Mirror, of which the following is a specification.

This invention relates to devices used for reflecting objects and occurrences rearwardly of the user.

One of the objects of this invention is to provide a device that can be applied to the hand of the user in such a manner that by a suitable holding of the hand, while looking ahead, one may see and observe objects and occurrences in the rear.

Another object is to provide such a device, since preferably small, with a convex reflecting face, in order to enlarge the reflection.

Other objects will appear from the following description and appended claims as well as from the accompanying drawings, in which

Fig. 1 is a face elevation of a mirror embodying the invention, a hand being illustrated in dotted lines, showing the approximate proportions of the device.

Fig. 2 is an edge elevation of the device in Fig. 1, the handle-portion of the device being broken away.

Fig. 3 is an edge elevation of the device at about right angles to the illustration of Fig. 2, of a slightly modified form, having loop-like members through which a strap may be passed for attaching the device.

This device is of very broad utility. The driver of a vehicle, like an automobile, may with advantage use the device, while holding the driving or steering wheel, when the hand may be in a position as illustrated in Fig. 1, or by stretching out the arm, eventually obtaining a reflection of objects or occurrences back of his own car. A traffic policeman, while watching the traffic in one direction, may observe the traffic back of him. A pedestrian, or, in fact, any one who may have to be in heavy traffic may protect himself by a device of this type.

The hand, illustrated in dotted lines in Fig. 1, indicated at 4, shows the fingers

slightly bent in a position in which the hand may control a steering wheel of an automobile. The mirror 6 is provided with strips or band-like fastening or supporting members 7, projecting from the rear side of the device, as illustrated in Fig. 2, to engage over the hand or arm of the user. These strips or bands may be of metal or any other similar spring-like material, as of celluloid. The housing or frame of the mirror may also be of metal or any other similar suitable material. A handle or manipulating member 5 is provided to facilitate a pointing or facing of the mirror to a desired direction.

A man can, for instance, easily hold a steering wheel firmly, and still have a finger, or especially the thumb, free for tilting or manipulating the mirror. The handle-member 5 is preferably shaped and disposed to facilitate such manipulating.

The slightly modified form, illustrated in Fig. 3, is provided with loop-like bands or members 8, allowing the use of straps of flexible material, as of cloth, or leather, indicated at 9.

It will easily be understood without further illustration that the device can be made attractive and light, in order to induce and allow ladies as well as men to make use of this invention, within the scope of the invention.

The front face of the reflector, indicated at 14, is preferably convex, since the device should be of small size. The attaching members 7 may also be applied to a wrist watch, either, to the front or rear.

Having thus described my invention, I claim:

1. In a wrist mirror, a reflecting face, connecting means extending from the back of the reflecting face adapted to hold the device to the hand of the user, and means extending sidewise from the device adapted to form operating means to allow a tilting of the device by one of the digits of the hand.

2. In a wrist mirror, a reflecting member, connecting means of spring material extending rearwardly from the reflecting member having its ends slightly bent upon the cen-

ter portion and adapted to allow a quick applying and removing and manipulating means adapted to allow a change of reflection and vision through the reflecting member by one of the digits of the hand to which the device is applied while the hand of the user remains fixed in a certain position.

In testimony that I claim the foregoing as my invention I have signed my name in the presence of two subscribing witnesses.

WILLIAM A. HOLQUIST.

Witnesses:

O. H. KRUEGER,
JESSIE A. MANOCK.
